UNITED STATES PATENT OFFICE.

HERMAN L. GREVE, OF BROOKLYN, NEW YORK, ASSIGNOR TO INTERNATIONAL MAILING TUBE AND WRAPPER COMPANY, OF BROOKLYN, NEW YORK, A CORPORATION.

CORDAGE WRAPPER.

Application filed January 25, 1921. Serial No. 439,741.

To all whom it may concern:

Be it known that HERMAN L. GREVE, citizen of the United States, and resident of the borough of Brooklyn, in the county of Kings and State of New York, has invented certain new and useful Improvements in Cordage Wrappers, of which the following is a specification.

My invention relates to cordage wrappers and packages and the object of my invention is to provide a wrapper by means of which a hank of rope or cord may be wrapped in such a manner as to prevent a single loop or all of the rope from being withdrawn from the package until after the wrapper has been broken or unlocked. A further object is to provide a complete package by means of said wrapper.

A further object is to provide a wrapper that can be made at a low cost and also one that can be folded quickly to inclose the rope and locked quickly and securely about the same.

Referring to the drawings which form a part of this specification,

Fig. 1 is a view of the inner side of a wrapper embodying my invention;

Fig. 2 is a perspective view of the wrapper as it appears after a portion of the hank, usually one-half thereof, is secured in the wrapper;

Fig. 3 is a view disclosing the appearance of the package fully wrapped; and

Fig. 4 is a cross-sectional view taken on line 3-3 of Fig. 3.

A indicates the body portion of the wrapper which may be constructed of tough flexible paper or other suitable material and preferably formed rectangular in shape as illustrated. A portion of the material is cut out to provide an opening B through which the arms C'-C' respectively of the metal fastener C are passed and bent over against the body portion A of the wrapper as shown in Fig. 2, after enclosing one-half of a hank of rope by passing the end A' of the wrapper through the opening between the loops of the rope of a complete hank. A piece is also cut from the body portion A to provide an opening D through which the catch E is inserted, the hook portion E' engaging the wrapper as illustrated in Fig. 4, and the end portion E² projecting under the wrapper to prevent the catch

from easily unhooking. Both fastening means C and E are permanently connected to the body portion A by means as illustrated and well known in this art. After the wrapper is fastened as illustrated in Fig. 2, the end A² of the wrapper is folded over the remaining half of the hank and the catch E is secured to the wrapper thus completing the package.

By leaving the hanks connected by a portion of the rope F, a long rope may be provided by assembling the hanks in close relation.

It will be observed that the fold G of the wrapper is disposed between the loops formed at each end of the hank and therefore when one end of the rope or a loop thereof is pulled longitudinally of the wrapper, it contacts the edge of the intermediate fold G, which being supported on both sides by the rope may crush to a certain extent but will not give way and therefore the hank or a part thereof cannot be removed from the wrapper without either unlocking it or tearing it bodily from the rope.

Having thus described my invention I claim as new:

1. A wrapper comprising a sheet of flexible material having two independent fastening and unfastening means located one at each end thereof, said sheet having openings to receive said fastening means located in alignment therewith.

2. A wrapper having a metallic means at each end thereof whereby the ends may be fastened to or unfastened from the body portion of the wrapper.

3. A wrapper having two openings in the body portion thereof and means insertable through said openings whereby the ends may be fastened to or unfastened from the body portion of the wrapper, the means and the openings being in alignment.

4. A wrapper having two openings in the body portion thereof and means insertable through said openings whereby the ends may be fastened to or unfastened from the body portion of the wrapper, to form two cylinders, one within the other.

5. A wrapper having two holes therein and two fastening or unfastening means at the opposite ends of the wrapper, the fastening means at one end being adapted to be

inserted through the hole nearest thereto whereby a small cylinder is formed, the fastening means at the other end being adapted to be inserted through the hole nearest thereto whereby a larger cylinder is formed which latter cylinder surrounds the small cylinder.

Signed at the borough of Brooklyn, in the county of Kings and State of New York this 22nd day of January, A. D. 1921.

HERMAN L. GREVE.
